UNITED STATES PATENT OFFICE.

MAX LITTMANN, OF ST. LOUIS, MISSOURI.

DESIGN FOR A HAME-HOOK.

SPECIFICATION forming part of Design No. 32,997, dated July 24, 1900.

Application filed June 11, 1900. Serial No. 19,961. Term of patent 7 years.

To all whom it may concern:

Be it known that I, MAX LITTMANN, a citizen of the United States, residing at the city of St. Louis, in the State of Missouri, have invented and produced a certain new and original Design for a Hame-Hook, of which the following is a specification, reference being had to the accompanying drawing, forming a part thereof.

10 The drawing shows a perspective view of a hame-hook embodying my new design.

As shown in the drawing, the leading or material feature of my design consists of a hame-hook having the two vertical slots 2 and 15 4 connected by a horizontal slot 3 and the horizontal slot 5 leading from the vertical slot 4 in the same direction with and parallel to the horizontal slot 3.

20 The design consists of a flat piece of metal provided with a cylindrical coil 8 at one end

and a rounded outer portion. The hame-hook is provided with a vertical groove 2, from which extends a horizontal groove 3. A vertical groove 4 extends from the groove 3, and the horizontal groove 5 extends from the vertical groove 4, parallel with and immediately under the horizontal groove 3. A tongue 7 extends between the horizontal grooves 3 and 5 and forms one wall of all of the grooves, the free or inner end of said tongue 7 extending beyond the free end of the tongue 6, the tongue 6 forming the upper wall of the groove 3.

25 I claim as my invention—

30 The design for a hame-hook herein shown and described.

35 MAX LITTMANN.
